US00D977087S

(12) **United States Design Patent** (10) Patent No.: **US D977,087 S**
(45) Date of Patent: **** Jan. 31, 2023**

(54) **PATIENT INTERFACE**

(71) Applicant: **Fisher & Paykel Healthcare Limited**,
Auckland (NZ)

(72) Inventors: **Silas Sao Jin Siew**, Auckland (NZ);
Wen Dong Huang, Auckland (NZ);
Craig Robert Prentice, Auckland (NZ);
Andrew Paul Maxwell Salmon,
Auckland (NZ)

(73) Assignee: **Fisher & Paykel Healthcare Limited**,
Auckland (NZ)

(**) Term: **15 Years**

(21) Appl. No.: **29/695,067**

(22) Filed: **Jun. 14, 2019**

(56)

CLAIM

The ornamental design for a patient interface, as shown and described.

DESCRIPTION

FIG. 1 is a perspective view of a patient interface which incorporates our design;

FIG. 2 is an alternate perspective view of the patient interface;

FIG. 3 is a top plan view of the patient interface;

FIG. 4 is a bottom plan view of the patient interface;

FIG. 5 is a left side elevational view of the patient interface;

FIG. 6 is a front elevational view of the patient interface;

FIG. 7 is a right side elevational view of the patient interface; and,

FIG. 8 is a rear elevational view of the patient interface.
